UNITED STATES PATENT OFFICE.

HENRY R. BUTTERFIELD, OF WATERVILLE, MAINE.

ELECTRIC STEAM-GENERATOR AND WATER-HEATER.

SPECIFICATION forming part of Letters Patent No. 437,771, dated October 7, 1890.

Application filed September 12, 1889. Renewed May 15, 1890. Serial No. 351,846. (No model.)

To all whom it may concern:

Be it known that I, HENRY R. BUTTERFIELD, a citizen of the United States, residing at Waterville, in the county of Kennebec and State of Maine, have invented certain new and useful Improvements in Steam-Generators and Water-Heaters; and I do hereby declare the following to be a full, clear, and exact description of the invention, such as will enable others skilled in the art to which it appertains to make and use the same.

This invention relates to devices for generating steam by heat due to electricity or heating water to a less degree by the same means.

The object of said invention is to increase the simplicity and efficiency of such devices. This object I attain by a wire coiled on a tube of non-conducting material and in closed within another layer of the same, and a metallic rod extending from end to end of the tube and having one end of the wire attached thereto, said wire and rod forming part of an electric circuit, these heating devices being immersed in the water of a boiler or other receptacle and duplicated or multiplied to any necessary extent.

In the accompanying drawings, Figure 1 represents a perspective view, partly broken away, of a furnace having a boiler therein provided with my electric heating-tubes. Fig. 2 represents a detail perspective view of one of said tubes, the outer envelope being turned back at one end to show the wire. Fig. 3 represents a similar view of the same tube broken in the middle for the same purpose. Fig. 4 represents a perspective view of the entire tube as it normally appears. Fig. 5 represents a detail view of the rod before referred to. Fig. 6 represents detail view of the disks which close the ends of the tubes and are perforated centrally for said rods.

A designates a furnace, B a boiler within the same, and C the electric heating-tubes running longitudinally, as shown, after the usual arrangement of fire-tubes, although I do not limit myself to any particular number, location, or position. Each of these heating-tubes consists of an interior tube D, of some non-conducting material, a wire E, wound thereon, an exterior tube or layer F,

of non-conducting material, centrally-perforated disks G H, of non-conducting material, closing the ends of the tube, and a rod I, of conducting material, extending from end to end of the tube through the central perforations g h of said disks and having an eye I' at one end to receive the proximate end of the wire E. This practically brings the termini of the coil very near each other, which is frequently very convenient in connecting said wire coils in circuit. It would be possible to dispense with the rod and carry an extension of the wire E back through the tube instead; but the rigidity of the rod and the central perforations of the disks enable said rod to brace the tube as a whole, besides maintaining accurately its central position.

Of course water may be heated in this manner for use in warming dwellings or other structures, or for any other service which requires heated water or steam. The same devices may also be used for raising the temperature of any other substance besides water, whether liquid, solid, or gaseous.

I prefer that the wire of the coil should be naked. If wound with care, there is no danger of short-circuiting; but it may of course be covered without departing from my invention.

Having thus described my invention, what I claim as new, and desire to secure by Letters Patent, is—

1. In combination with a non-conducting tube, a wire wound thereon and forming part of an electric circuit, a layer or outer tube of non-conducting material inclosing said wire, and a conductor extending from one end of said wire through said tube to the other end thereof, substantially as set forth. 90

2. A non-conducting tube, a wire wound thereon and forming part of an electric circuit, an outer layer or tube of non-conducting material inclosing said wire, and perforated disks of non-conducting material closing the ends of said tube, a conductor being extended through the perforations of said disk from one end of said wire to the other end of said tube, so as to be near the other end of said wire, substantially as set forth. 100

3. In combination with a tube of non-conducting material, a wire wound thereon, disks

closing the end of said tube, and a rod of conducting material extending through the perforations in said disks, one end of the wire being attached to said rod, substantially as set forth.

5. A tube of non-conducting material, a wire wound thereon, an outer layer or tube of non-conducting material inclosing said wire, and a rod extending from one end of said wire through said inner tube to the vicinity of the other end of said wire, substantially as set forth.

10. A boiler or other receptacle for water to be heated, in combination with electric heating-tubes arranged therein, each tube consisting of a non-conducting inner tube, a non-

conducting outer tube, a wire wound between them, and a rod extending from one end of said wire through said tube, substantially as set forth.

20. 6. An electric heating-tube consisting of two tubes of non-conducting material with wire between them, disks closing the ends of said tube, and a rod extending from one end of said wire through perforations in said tubes, substantially as set forth.

In testimony whereof I affix my signature in presence of two witnesses.

HENRY R. BUTTERFIELD.
